DESIGN FOR A COAT HANGER

John Martin Cless, West Los Angeles, Calif.

Application January 2, 1947, Serial No. 135,889

Term of patent 3½ years

(Cl. D80—8)

To all whom it may concern:

Be it known that I, John M. Cless, a citizen of the United States and a resident of West Los Angeles, in the county of Los Angeles and State of California, have invented a new, original, and ornamental Design for a Coat Hanger, of which the following is a specification, reference being had to the accompanying drawings, forming a part thereof.

Figure 3 is a side elevational view of the coat hanger depicted in Figures 1 and 2; and hanger of my design depicted in Figures 1, 2, and 3.

I claim:

The ornamental design for a coat hanger, substantially as shown.

JOHN MARTIN CLESS.
